LINE GUIDE TO ENABLE THE BLIND TO
WRITE SCRIPT

Harry G. Hill, Los Angeles, Calif.

Application March 21, 1936, Serial No. 70,096

5 Claims. (Cl. 35—38)

This invention relates to devices for assisting in the writing of script and particularly to a device for guiding the lines of such writing.

At the present time blind persons experience considerable difficulty in writing longhand, this being due to the tendency for adjacent lines of writing to overlap each other.

It is an object of this invention to enable blind persons to write longhand in reasonably straight lines.

Another difficulty encountered by blind persons attempting to write longhand is in the matter of keeping within definite margins.

Another object of this invention is to enable blind persons, when writing longhand, to keep within definite marginal lines.

Still another object is to permit the location of margin and/or writing lines to be selectively determined.

Yet another object of the invention is to provide a writing board for the blind which is inexpensive to manufacture, light and easy to carry and of enduring construction. The manner of accomplishing the foregoing objects as well as further objects and advantages will be made manifest in the following description taken in connection with the accompanying drawing in which:

Fig. 1 is a perspective view of a preferred embodiment of my invention.

Fig. 2 is a transverse sectional view taken on line 2—2 of Fig. 1.

Referring specifically to the drawing, the preferred embodiment of the invention, as shown therein, comprises a writing board 10 including a rectangular base 11 having parametric walls 12 formed integral therewith and extending around all four edges thereof. The upper face of the base 11 provides a smooth writing surface. The area of the surface 13 is preferably slightly over 8½ x 11 inches so as to take letter-size paper, though it may be of any other desired dimension. Slots 14 are formed in the wall 12 near two of its corners as shown in Fig. 1, these slots receiving hinge plates 15 of a guide-supporting frame 16, which is preferably built to fit neatly into the space within the wall 12. The plates 15 are nailed to the frame 16 as indicated in Fig. 1 and are pivotally related to the base 11 by nails 17 which extend inwardly through the wall 12 and suitable apertures formed in the hinge plates 15.

The frame 16 is preferably rectangular and includes side members 18 which are held in parallel spaced relation by upper and lower cross members 19. Side members 18 on the frame 16 have a

series of notches 20 which serve to receive a line guide cord 21, or other similar element of a filamentary character which extends back and forth across the frame 16 in parallel strands 22.

The upper and lower cross members 19 are relieved by shallow notches 25 to provide room for clips 26 between which is stretched a margin guide string 27. The clips 26 are easily slideable along the notches 25 to adjust the lateral position of the guide string 27.

10

Operation

In using the preferred form of the invention hereinabove described, the writer opens the device 10 by swinging the frame 16 upwardly about the hinge nails 17 and inserts a sheet of paper 30 onto the base 11 within the wall 12. The frame 16 is now swung downwardly into the closed position in which it is shown in Fig. 1. The writer now adjusts the clips 26 to place the margin guide string 27 where it will indicate the correct margin at the left-hand side of the sheet 30. Having accomplished this the writer takes up the pencil 32 and feeling his way along the uppermost guide strand 22 to proper distance from the right-hand frame member 18, the writer starts to write in the space immediately above wherein he feels the topmost strand 22 with the point of his pencil. As the writer comes down with the pencil 32 in the completion of each letter he feels the contact of the pencil with the strand 22 thereby letting him know that he is writing in the straight line as guided by that uppermost strand. The right hand of the writer, of course, contacts the right-hand frame side member 18 before he has written over to the right-hand edge of the paper and he, therefore, has a warning that he is approaching the right-hand edge of the paper. He, therefore, is able to end his writing on that line at a proper grammatical stopping place and proceed to the next line. When writing with the right hand a blind person preferably follows the pencil, as it travels along the guide strand just below the line of writing, with his left forefinger as indicated in Fig. 1. Thus, when arriving at the right end of the line, it is easy for the left forefinger to be shifted down to the next strand 22 and follow this over to the left-hand side of the paper where the writer may then commence with the next line of writing. Owing to the flexibility of the strands of string 22 the writer may flex one of these downwardly for the purpose of writing the lower loop of the letters *f, g, j, p, q, y* and *z* after which

the string resumes its normal tension and straight tautness.

After the sheet 30 has thus been written on to whatever extent desired the frame 18 is raised and 5 the paper 30 removed therefrom. This sheet of paper may then be reversed and again placed in the device or a fresh sheet may be placed therein. Where it is necessary or desirable to adjust the writing guide line relative to the paper, the 10 string 21 may be removed from the frame 16 and the paper be inserted in the device beneath the string 27 so that this will serve as the proper guide for the writing to be placed on the paper. The guide 27 may then be shifted to various 15 positions over the paper where writing is necessary without removing the paper from the device. It is to be understood, of course, that similarly shiftable guide strings in groups of one or more strings might be provided to operate in substantially the 20 same manner on the side frame members 18 as the guide string 27 and clips 26 operate on the frame cross members 19.

It is to be noted that each of the strands 22 has to pass a certain distance horizontally under- 25neath each of the frame side members 18 before it passes upwardly into one of the notches 29. This results in these strands possessing, clear up to the 30 portions of lines of writing disposed just within the frame side members 18 that flexibility which permits these strands to accommodate downward 35 movements of the pencil 32 in writing certain letters as already noted hereinabove.

While the guide strands of my device are preferably formed of string they may be formed of any 35 other filamentary member which will give substantially the same beneficial results.

It is also to be understood that while I have shown and described but a single embodiment of 40 my invention various modifications may be made in this without departing from the spirit of the invention or the scope of the appended claims.

What I claim is:

1. In a device for aiding in writing longhand, the combination of: a frame including two members adapted to extend along opposite edges of a 45 piece of writing material; and a plurality of strands of a resilient nature connected at their opposite ends to said members at points disposed substantial distances outward from inner edges of 50 said frame members and therefore substantially free to swing parallel with said writing material at said inner edges of said frame members, said strands lying sufficiently close to said writing material to flexibly guide a pencil in the hand of a 55 person writing on said material.

2. In a device for aiding in writing longhand, the combination of: a writing board; a wall along

the edges of said board centralizing a piece of paper deposited therein; a frame pivotally attached to said board, said frame being adapted to swing downward inside of said wall and on top of said paper to hold said paper on said board; a plurality of parallel strands of a resilient nature stretched across said frame, said strands lying sufficiently close to said paper to flexibly guide a pencil in the hand of a person writing on said paper; and marginal guide means located along at least one side of said paper and disposed a substantial distance inwardly from the points on said frame at which said strands are connected thereto.

3. In a device for aiding in writing longhand, 15 the combination of: a writing board; a frame pivotally attached to said board, said frame being adapted to swing downward on top of said paper to hold said paper on said board; a plurality of parallel strands of a resilient nature stretched 20 across said frame, said strands lying sufficiently close to said paper to flexibly guide a pencil in the hand of a person writing on said paper; and marginal guide means located along at least one 25 side of said paper and disposed a substantial distance inwardly from the points on said frame at which said strands are connected thereto.

4. In a device for aiding in writing longhand, the combination of: a writing board; a wall along the edges of said board centralizing a piece of 30 paper deposited therein; a frame pivotally attached to said board, said frame being adapted to swing downward inside of said wall and on top of said paper to hold said paper on said board; and a plurality of parallel strands of a resilient 35 nature stretched across said frame, opposite ends of said strands being secured in place on said frame at points which along at least one side of said frame are disposed substantial distances outward from an adjacent inside frame edge, said 40 strands lying sufficiently close to said paper to flexibly guide a pencil in the hand of a person writing on said paper.

5. In a device for aiding in writing longhand, the combination of: a writing board; a frame pivotally attached to said board, said frame being adapted to swing downward on top of said paper to hold said paper on said board; and a plurality of parallel strands of a resilient nature stretched 45 across said frame, opposite ends of said strands being secured in place on said frame at points which along at least one side of said frame are disposed substantial distances outward from an adjacent inside frame edge, said strands lying sufficiently close to said paper to flexibly guide a pencil in the hand of a person writing on said paper.

HARRY G. HILL.
